(57) **CLAIM**

The ornamental design for a mesh container, as shown.

DESCRIPTION

FIG. 1 is a perspective view of a mesh container showing my new design;

FIG. 2 is a front view thereof;

FIG. 3 is a rear view thereof;

FIG. 4 is a left side view thereof, the right side view being a mirror image;

FIG. 5 is a top view thereof;

FIG. 6 is a bottom view thereof;

FIG. 7 is a perspective view of a second embodiment of my new design;

FIG. 8 is a perspective view of a third embodiment of my new design; and,

FIG. 9 is a perspective view of a fourth embodiment of my new design.
